Primary Examiner — Brian N Vinson(74) *Attorney, Agent, or Firm* — Fletcher Yoder, P.C.(57) **CLAIM**

The ornamental design for a collapsible suspended lighting assembly, as shown and described.

DESCRIPTION

FIG. 1 is a perspective view of a collapsible suspended lighting assembly showing my new design;
 FIG. 2 a front elevational view thereof; and,
 FIG. 3 is a side elevational view thereof.

The broken lines in the drawing represent portions of the assembly which form no part of the claimed design.

1 Claim, 3 Drawing Sheets(56)
